UNITED STATES PATENT OFFICE.

JOHN B. BRESSLER, OF GRASS VALLEY, OREGON.

WASHBASIN AND SINK.

1,320,984.

Specification of Letters Patent.

Patented Nov. 4, 1919.

Application filed April 25, 1919. Serial No. 292,754.

To all whom it may concern:

Be it known that I, JOHN B. BRESSLER, a citizen of the United States, residing at Grass Valley, in the county of Sherman and 5 State of Oregon, have invented new and useful Improvements in Washbasins and Sinks, of which the following is a specification.

This invention relates to washbasins, 10 sinks or the like, and comprehends the provision of a water container utilized as such, the container being pivotally mounted upon the wall or other suitable support to assume a horizontal position for use, in a position 15 parallel to the wall of such support when folded.

In carrying out my invention I combine with such a container a waste receiving tank located within the wall or support from 20 view, the tank communicating with the container and adapted to receive the contents thereof as the container is elevated to its folded position, the tank being piped to the sewer in the usual manner.

25 One of the chief characteristics of the invention resides in providing the above mentioned waste tank with a closure for controlling the communication between the same and said container the closure normally cutting off all communication, thus excluding 30 all objectionable odors from the tank gaining access to the room, the closure being automatically open while the container is being folded to permit the contents thereof to be 35 emptied into the tank.

Another object of importance resides in the fact that the container utilized as either a wash basin or sink is free of any drain or 40 outlet, thus eliminating use of a plug or stopper therefor; while the container when folded conceals the spigot or spigots to prevent the sediments or accumulation of dust thereabout, all of which renders the invention very sanitary.

45 The nature and advantages of the invention will be better understood when the following detailed description is read in connection with the accompanying drawing, the invention residing in the construction, 50 combination and arrangement of parts claimed.

In the drawings forming part of this specification, like numerals of reference indicate similar parts in the several views, 55 and wherein:

Figure 1 is a perspective view of the

water container projecting from the wall in a horizontal position for use.

Fig. 2 is a similar view showing the container folded in parallelism with the wall. 60

Fig. 3 is a central vertical sectional view.

Fig. 4 is a side elevation of the invention removed from the wall, with the water container horizontally disposed.

Fig. 5 is a vertical sectional view there- 65 through showing the container partly elevated in a manner of automatically opening the closure for the waste receiving tank.

Fig. 6 is a transverse sectional view.

The invention essentially embodies a 70 water container 10, and a waste receiving tank 11 secured to the opposite side of a panel 12, the latter being adapted to be secured upon a wall or other suitable support to lie flush therewith. Consequently, the 75 wall or support A is suitably cut-away to accommodate the waste receiving tank 11 which is mounted upon that side of the panel lying next to the wall.

The water container 10 may be construct- 80 ed from any suitable material and may also vary in design without departing from the spirit of the invention, the container 10 having secured thereto a transversely disposed rod 13 having its ends journaled in bearings 85 14, whereby the container 10 is mounted upon the panel 12 for vertical swinging movement. The container is adapted to assume a horizontal position for use as illustrated in Fig. 1, but when its use is not de- 90 sired it can be readily and easily folded to lie against the partition 12 in parallelism therewith. A suitable handle 15 is provided for the container 10 for moving the latter to either of its positions. Projecting 95 from the partition 12, are the hot and cold water spigots 16 and 17 respectively, these parts being so disposed with regard to the container 10 as to be concealed from view and completely housed by the container 100 when the latter is in its folded position. By reason of this fact, the spigots are not exposed under normal conditions, to accumulate dust or dirt and consequently it does not require much time or labor to maintain 105 the parts in a sanitary condition.

The panel 12 and the adjacent wall of the tank 11 are provided with an opening establishing communication between the container 10 and said tank, for the purpose of 110 allowing the container to empty into the tank as the container is swung from its hori-

zontal to its folded position against the panel. Leading from the tank 11 is a waste pipe 18 while supported above the pipe and in spaced relation to the bottom of the tank 5 is a strainer 19 removably seated upon a plurality of lugs 20 projecting from the opposed walls of the tank. With a view of excluding from the room, objectional odors from the tank 11, I provide a pivoted closure 21 for controlling the communication between the tank and container, any suitable means being employed to maintain the closure in its closed position when the container is in horizontal position. As shown 10 in this specific instance, a yieldable element 22 is employed for this purpose.

While as stated the container may be of any suitable design it is herein shown as being provided with outwardly extending 20 flanges 23 projecting from one side and the end wall thereof, the flanges effectively engaging the panel about the edges of the opening therein, when the container is in folded position to exclude from the room 25 objectional odors from the tank.

For the purpose of automatically swinging the closure 21, to an opened position when the container 10 is being elevated, I provide the end walls of the container with 30 upwardly and rearwardly extending flanges 24 which when the container is in horizontal position is slightly spaced from the closure 22, but disposed relatively thereto so as to engage the closure when the container 35 is elevated, thus moving the closure to an open position to permit the container to empty into the tank 11. In addition to this purpose, the flanges 24 serve to direct the contents from the container into the tank, 40 as they prevent spilling of the contents over this end of the container. The closure 22 is provided with a handle 25 whereby the closure may be manually opened against the tension of the element 22 while the container 45 is in horizontal position. Thus access may be readily had to the tank to remove anything therefrom, that might casually fall into the tank from the container.

Arising from a cleat 26 secured to the 50 rear of the panel 12, is a leaf spring 27 disposed in the path of movement of the crank-like extremity 28 of the rod 13 which pivotally supports the container 10. The rel-

ative disposition of these parts is such, that the spring 27 engages the extremity 28 of 55 the rod 13 to immovably hold the container 10 in a horizontal position, and when the container is moved to its vertical position, the spring effectively engages the extremity 28 of the rod to hold the container in its 60 folded position. Carried by the container is a hook-like element 30 adapted to coöperate with a similar element 31 while projecting from the panel 12 to brace the container 10, when the latter is in horizontal 65 position. When the latter is lowered to this position, the element 30 is moved into engagement with its coöperating element 31.

While I have shown and described what I consider the preferred embodiment of the 70 invention, I desire to have it understood that I do not limit myself to the exact construction, and arrangement of parts disclosed, inasmuch as such changes may be resorted to when desired as fall within the 75 scope of what is claimed.

What I claim is:—

1. In combination, a fixed support having an opening, a water container pivotally mounted upon one side of the support for 80 vertical swinging movement, a stationary waste receiving tank arranged at the opposite side of the support and communicating with the container through said opening, a closure controlling the communication between said opening and mounted for pivotal movement, yieldable means for holding the closure in closed position when the water container is horizontally disposed, means whereby the closure is automatically opened 85 against the tension of said yieldable means when the container is elevated.

2. In combination, a water container, pivotally mounted for vertically swinging movement, a stationary waste receiving tank 95 communicating therewith, a shaft associated with said container for movement therewith and including an angular offset extremity, a leaf spring, said spring being disposed in the path of movement of said offset angular 100 extremity of the shaft to engage the latter to hold said container in either vertical or horizontal position.

In testimony whereof I affix my signature.

JOHN B. BRESSLER.
